OF NEW YORK, N. Y., A CORPORATION OF DELAWARE.

VAPORIZING APPARATUS FOR INTERNAL-COMBUSTION ENGINES.

1,245,129.

Specification of Letters Patent.

Patented Oct. 30, 1917.

Application filed March 31, 1917. Serial No. 158,922.

To all whom it may concern:

Be it known that I, JOHN E. SMITH, a citizen of the United States, residing at the city of New York, county of New York, and State of New York, have invented certain new and useful Improvements in Vaporizing Apparatus for Internal-Combustion Engines; and I do declare the following to be a full, clear, and exact description of the invention, such as will enable others skilled in the art to which it appertains to make and use the same.

My present invention pertains to an improved apparatus for use in connection with internal explosion or combustion engines, whereby liquid fuels, such as kerosene or gasoline, alcohol, or the like, may be employed.

The main object of the invention is to provide an apparatus wherein liquid fuels generally, such as kerosene or other hydro-carbon fuel, or denatured alcohol, may be utilized to their fullest extent, and so vaporized that they may be led directly to the engine cylinder or cylinders and there exploded or consumed as vapor to effect work.

A further object of the invention is to provide an apparatus wherein kerosene or other liquid fuel may be transformed into a vapor so that it will not deposit the carbon either in or upon the heater in which it is vaporized, or in or upon the working parts of the engine.

A still further object of the invention is to provide an apparatus whereby the exhaust gases of the engine may be utilized to heat the kerosene or other fuel, and to so regulate the heating of the fuel that the apparatus will deliver to the working space of the engine the proper quantity of fuel to meet the needs of the engine under varying or changing conditions of load.

The following description is made with especial reference to kerosene as a fuel, and in this connection I would say that the method and apparatus herein set forth and described are the same, irrespective of the particular fuel employed. One form of apparatus whereby the invention may be utilized and carried out is shown in the annexed drawings, wherein:

Figure 1 is a side elevation thereof;

Fig. 2 a vertical transverse sectional view of the apparatus, taken on the line 2—2 of Fig. 1;

Fig. 3 a perspective view of a portion of the apparatus, the parts being separated to more clearly show the heat-transferring chamber wherein the kerosene is vaporized;

60

Fig. 4 a horizontal sectional view of the hollow chamber in which the heater is enclosed, and designed to show more particularly the by-pass passage for the exhaust gases and the valve controlling the same, 65 by which the varying conditions of the temperature of the outside air or atmosphere may be provided for.

Referring to the drawings, 1 denotes generally a carburetor of any approved type (Schebler) to which the kerosene (instead of gasoline) is passed through a pipe 2, the main supply of air passing in through a pipe 3, while the auxiliary supply of air passes in through an auxiliary valve 4, 70 which is adjustable, so that the amount of air passing in may be determined and regulated to meet varying conditions. 5 is the needle valve regulator.

The carburetor is connected at its upper end to the lower portion or end of a hollow chamber or casing, designated as a whole by 6, and in which is mounted what may be termed the vaporizer, hereinafter set forth in detail, through which the mingled air 85 and kerosene pass. Upon the upper end of the chamber 6 is secured a hollow head or casting 7, to which in turn is connected the manifold 8, opening into valve chambers or working spaces of the motor cylinders. 90 Said head is provided at its opposite end with an auxiliary air intake 9, adjustable through stem 10, serving, when necessary, to admit air to the vaporized kerosene, the air preferably being discharged into the gas at 95 an angle to the flow thereof so as to cause a thorough intermingling of the gas and air prior to its discharge into the manifold 8.

A valve-controlled gasoline feed pipe 11 opens into the head 7 and from which gasoline is admitted for the purpose of starting the motor, said pipe preferably entering the head in advance of the usual butterfly throttling valve 12.

Secured to one of the side walls of the chamber 6, in line with an opening therein, is the exhaust manifold 13, while connected to an opening formed in the opposite side is a discharge pipe 14 for the exhaust gases.

The vaporizer proper or heat-transfer de- 110

vice, which is preferably a unitary structure and which may be bodily inserted into and removed from the chamber 6, is preferably formed from a series of superposed metallic tubes arranged in separated tiers. The tubes of one tier are laid one upon the other, and the adjacent tiers are separated from each other, as by wires, one at each end, the tube ends and wires being soldered, dipped 10 or sweated together to form a gas-tight union between the parts. There is thus formed a series of relatively long passages or chambers 15, through which the mixed air and kerosene pass, and a series of transverse channels or ways 16 (in fact, the tubes proper) through which the exhaust products and gases of combustion pass.

Plates 17 and 18 are soldered to the top and bottom of the tube tiers, said plates being provided with ports or openings which register with the passages 15. One side of the chamber 6 takes the form of a removable cover 19, which admits of the ready insertion and removal of the gasifier as an 25 entirety.

The tubes are preferably formed of copper or other metal having a high degree of conductivity and capable of withstanding the corrosive action of the exhaust gases. 30 In practice the metal of the tubes has been of 5/1000 inch thickness, and the tubes of 5/16 inch outside measurement. The channels are approximately one-eighth inch in width, such dimension being determined by 35 the spacing wires above referred to inserted between the various tiers of tubes. The length of the passages 15, that is, the distance from the bottom plate 17 to the top plate 18, is dependent upon several conditions; primarily, the thickness of the walls, 40 and the width of the passages. The third dimension, that is, the breadth or measurement from edge to edge of the passage, is immaterial, except as the structure may be designed for larger or smaller motors or engines. Such dimensions are not stated by way of 45 limitation, but merely for the purpose of explanation, as I have successfully practised my method with an apparatus constructed in accordance with such details. Furthermore, as will be readily appreciated, 50 the vaporizer element may be constructed in various ways, so long as care is taken to have the passages, as 15, of such size that the kerosene will be heated to substantially the same temperature throughout.

As will be seen upon reference to Figs. 2 and 4, the casting or chamber 6 may be provided with a by-pass passage 20, which 55 opens at one end into the housing or chamber 6 adjacent the intake manifold 13. It then passes around the side of the casting or chamber and again discharges into it adjacent the exit to which the pipe 14 is connected. A valve 21, mounted upon a

stem 22, to which may be attached a control lever (not shown) is employed to control the passage of the exhaust gases through the by-pass. When in the full-line position, shown in Fig. 4, all of the exhaust gases pass in a direct path through chamber 6 and the contained vaporizer, but when the valve is thrown to the dotted-line position in said figure, a portion of the spent gases is deflected from the vaporizer 75 and caused to pass through the by-pass, and consequently the vaporizer will not become as hot as when the entire volume of exhaust gases passes therethrough.

In the utilization of vaporized kerosene 80 as a fuel, it is essential that the heat be so regulated and controlled that it is sufficiently high to convert the kerosene into a dry gas and yet at the same time the temperature must not be so high as to crack the 85 same; in other words, the temperature must not exceed 350° C.

Another and most essential point is that the kerosene must be heated through and through, and it is found that by making 90 the passages 15 relatively narrow this is accomplished.

The mixed air and kerosene as it passes from the Venturi tube of the carburetor may be said to be "wet," that is, the particles of oil are distributed throughout the air and thus pass into the lower end of the channels 95 15. In passing through the channels the kerosene is vaporized and finally issues therefrom as a dry gas which is ready for 100 instant use in the engine. The thin walls of the passages (which are made as thin as possible) permit quick radiation, and consequently quick heating of the oil particles. It is essential that the oil be completely 105 vaporized so that no unvaporized kerosene may be carried into the cylinder (or cylinders); otherwise such unvaporized particles would be cracked under the intense heat obtaining in the cylinder, causing a 110 deposition of carbon.

Again, the thin walls prevent undue accumulation of heat, a point of manifest advantage; thus, for instance, where the engine has been operating under heavy load, as in 115 the case of an automobile running up hill, the walls will quickly cool upon closing of the throttle, thereby preventing overheating of the gas and consequent cracking. The total mass of the walls of the vaporizer 120 must, however, be such that at low throttle there will be sufficient heat present to insure vaporization, and this is provided for by the tubular construction, as above set forth.

It is found in actual use of the structure 125 as above set forth that the temperature of the gas as it passes through the manifold is substantially constant, and this under varying conditions of load and speed of the engine. While the temperature of the exhaust 130

gases may materially rise, as it does when the motor is running fast, the construction of the heat-transfer device or vaporizer as above set forth, and the increased volume 5 of mixed fuel and gas which is drawn therethrough cause the temperature of the fuel mixture to remain substantially constant.

The speed of travel of the kerosene through the gasifier has been found upon a 10 Ford machine to be approximately 186 feet per second at 2000 revolutions per minute. The length of travel of the oil through the gasifier, or the length of the passages 15, is in proportion to the thickness of the walls, 15 the width of the passages and the speed of the motor.

The operation of the apparatus is as follows: To start the motor, a small amount of gasoline is admitted through pipe 11, which 20 is then closed and maintained so. Immediately the engine starts air is drawn into the carburetor through pipe 3, and the kerosene is likewise drawn up through the nozzle in the carburetor, intermingling with 25 the air and passing with the air in the form of a spray or mist into the lower ends of the passages 15. In going through the passages the entire oil content is subjected to a heat sufficiently high to transform it into a dry 30 vapor, and this without cracking the oil. The volume of air and oil passing through any one channel is so attenuated that each and every particle of oil will be subjected to the necessary and requisite degree of heat to 35 transform it from a wet state to a dry vapor. The thinness of the walls permits quick transfer of the heat from the spent gases (passing through tubes 16) to the air and oil, which mixture is heated evenly, or sub- 40 stantially so, throughout. In any event, it is found in actual use that the vapor thus produced is highly efficient and there is a minimum deposit of carbon in the engine cylinders.

45 The apparatus is normally designed to operate in cold weather; that is, the gasifier is so proportioned as to size and the number of tubes that the proper exchange of heat from the exhaust gases through the walls 50 of the tubes is such as to effect proper vaporization of the fuel. When, however, the atmospheric temperature increases, or, becomes higher, the full volume of exhaust gases may not be needed, at which time the 55 valve 21 will be opened to a greater or less extent and more or less of the exhaust gases by-passed around the gasifier. This arrangement is not essential when kerosene is employed as the fuel, but will be found ad- 60 vantageous when lighter fuels, such as gasoline, are employed.

The auxiliary air-inlet 9 is a precautionary measure, and its object is to insure a more thorough mixture of air with the dry 65 heated vapor.

While I have set forth somewhat in detail the transformation of the kerosene from a liquid condition to that of a dry vapor in which all the particles of the kerosene are transformed from the liquid to the dry 70 vaporized or gaseous state, it is to be understood that such explanation is given according to my present understanding of the transformation, and I do not desire to be limited thereby. Suffice it to say that the 75 apparatus has been commercially tested out under all conditions of weather, and the motor control has been proven to be highly flexible and responsive; in fact, more so than where the same car has been operated 80 under the usual motor equipment with gasoline as a fuel.

This application is, in part, a continuation of my copending application Serial No. 84,257, filed on or about March 15, 1916. 85

Having thus described my invention, what I claim is:

1. In a fuel-supplying system for engines of the internal-combustion or explosive type, the combination of a casing; a vaporizer 90 mounted in said casing, said vaporizer having thin walls and presenting a plurality of narrow spaces or passages for the flow of fuel therethrough, and with a series of relatively large passages for the flow of exhaust 95 gases; means for supplying a mixture of fuel and air to the fuel passages; a conduit leading from the fuel passages of the vaporizer to the working space of the engine; and means for conducting the exhaust gases 100 to the casing whereby the fuel content will be thoroughly vaporized and maintained at a proper working temperature under all working conditions of the engine, irrespective of variations in the temperature of the 105 exhaust gases.

2. In a fuel-supplying system for engines of the internal-combustion or explosive type, the combination of a casing, having an inlet and an exhaust port for exhaust gases and 110 likewise having an inlet and discharge port for the fuel; a vaporizer for the fuel mounted in the casing, said vaporizer comprising a plurality of thin-walled metal tubes, the metal whereof has a high degree of conductivity, said tubes being arranged in tiers, 115 said tiers being spaced apart to produce narrow passages therebetween, and said passages being in communication with the inlet and discharge fuel ports aforesaid; a carburetor connected to the inlet fuel port; and means for conducting the exhaust gases of the engine to the exhaust gas outlet port of the casing whereby the fuel content will be thoroughly vaporized and maintained at 120 a proper working temperature under all working conditions of the engine, irrespective of variations in the temperature of the 125 exhaust gases.

3. In a fuel-supplying system for engines 130

of the internal-combustion or explosive type, the combination of a casing, having an inlet and an exhaust port for exhaust gases and likewise having an inlet and discharge port 5 for the fuel; a vaporizer for the fuel mounted in the casing, said vaporizer comprising a plurality of thin-walled metal tubes, angular in cross-section, the metal whereof has a high degree of conductivity, said tubes 10 being arranged in tiers, said tiers being spaced apart to produce narrow passages therebetween, and said passages being in communication with the inlet and discharge fuel ports aforesaid; a carbureter connect- 15 ed to the inlet fuel port; and means for conducting the exhaust gases of the engine to the exhaust gas inlet port of the casing whereby the fuel content will be thoroughly vaporized and maintained at a proper work- 20 ing temperature under all working conditions of the engine, irrespective of variations in the temperature of the exhaust gases.

4. In a fuel-supplying system for engines of the internal-combustion or explosive type, 25 a manifold for the exhaust gases leading from the engine; a casing into which said manifold discharges; a vaporizer for the fuel located and housed within said casing, said vaporizer being formed with a plurality 30 of passages through which the exhaust gases pass and likewise with a plurality of relatively narrow passages for the passage of fuel; the walls of both sets of passages being formed of thin metal having a high degree 35 of conductivity; a carbureter connected to the casing and discharging into the same adjacent one end of the fuel passages; and a manifold extending from the casing adjacent the discharge ends of said fuel-pass- 40 sages and leading to the working space of the engine whereby the fuel content will be thoroughly vaporized and maintained at a proper working temperature under all working conditions of the engine, irrespective of 45 variations in the temperature of the exhaust gases.

5. In a fuel supplying system for engines of the internal combustion or explosive type, the combination of a hollow casing open at 50 its upper and lower ends and having oppositely-disposed inlet and exhaust ports for the introduction and discharge of exhaust

gases from the engine; a vaporizer mounted in said casing, said vaporizer presenting cross passages for the passage of the exhaust gases therethrough and relatively narrow passages for the passage of the engine fuel, the walls of such passages being formed of thin metal having a high degree of conductivity, whereby the heat from the gases 55 will be quickly transferred to the fuel, which latter will be heated through and through; a carbureter discharging into one end of the casing; and a manifold extending from the opposite end of the casing. 60

6. In a fuel supplying system for engines of the internal-combustion or explosive type, the combination of a hollow casing open at the top and bottom and along one side, and likewise having laterally-disposed openings 70 in its opposite sides; a vaporizer, comprising a series of thin-walled tubes arranged in separated tiers, and a plate secured upon the upper and lower ends of said tiers, respectively, and adapted to bear upon the 75 edges of the casing when the vaporizer is inserted in the casing; a cover plate closing the open side of the casing; a carbureter connected to the lower open end of the casing; a manifold in communication with the 80 upper open end of the casing; and a discharge pipe for the exhaust gases connected to one of the lateral openings in the casing.

7. In an engine, a carbureter; and a heat-interchange device located between the carbureter and the engine intake, said device having a plurality of narrow passages extending therethrough in communication with the carbureter and the intake of the engine, and a second series of larger passages 85 through which the exhaust gases of the engine are discharged, the walls between said passages being thin and formed of metal having a high degree of heat conductivity and the fuel passages being so proportioned 90 that the fuel content of the mixture passing therethrough will be thoroughly vaporized and maintained at a proper working temperature under all working conditions of the engine, irrespective of variations in 95 the temperature of the exhaust gases.

In testimony whereof I affix my signature.

JOHN E. SMITH.
